UNITED STATES PATENT OFFICE.

WILLIAM H. HOCKENSMITH, OF BRIDGEPORT, CONNECTICUT.

IMPROVEMENT IN SHUTTLES FOR SEWING-MACHINES.

Specification forming part of Letters Patent No. **140,041**, dated June 17, 1873; application filed May 28, 1873.

To all whom it may concern:

Be it known that I, WILLIAM H. HOCKENSMITH, of Bridgeport, in the county of Fairfield and State of Connecticut, have invented a new Improvement in Shuttle for Sewing-Machine; and I do hereby declare the following, when taken in connection with the accompanying drawing and the letters of reference marked thereon, to be a full, clear, and exact description of the same, and which said drawing constitutes part of this specification, and represents a front or the open side view of a shuttle.

This invention relates to an improvement in shuttles for sewing-machines, and particularly in that class which have a lever or bar arranged upon the inside, between which and the case the thread is drawn to produce the requisite tension; and the invention consists in combining with such bar or lever an auxiliary lever and screw working through the last-named lever, so as to bear one end of the said auxiliary lever upon the principal bar at a considerable distance from the screw, all as more fully and for the purpose hereinafter described.

A is the shuttle-case, within which the bobbin B is arranged in the usual manner. Within the case a lever, *a*, is arranged, between which and the case the thread is run in the

usual manner, and as seen in the drawing. This bar extends into a recess, C, in the shuttle-head, and beneath the bar an auxiliary lever, D, is arranged curved and extending back onto the bar *a* within the case. A screw, *b*, is set through the case, the lever D threaded to correspond to the said screw, the screw being free in the shuttle-case; therefore, by turning the screw, the lever D will be raised or lowered accordingly.

By raising the lever it bears upon the bar *a* at a considerable distance from the screw, and within the case, so that a better and more equal pressure is attained than when the bearing is made by a nut at the screw, or by the screw directly, and the turning of the screw in no way changes the position.

This construction, while affording a better tension, is considerably cheaper than other known constructions.

I claim as my invention—

In combination, with the tension-bar *a* within the shuttle-case, and extending into the recess C, the auxiliary lever D and adjusting-screw *b*, whereby the adjustment of the bar *a* is made through the said auxiliary lever D.

WM. H. HOCKENSMITH.
